UNITED STATES PATENT OFFICE

JOHN LAWLER MORGAN, OF CAMDEN, NEW JERSEY, ASSIGNOR TO JESSE SATENSTEIN,
OF CAMDEN, NEW JERSEY

TYING DEVICE

Application filed April 3, 1928. Serial No. 266,887.

My invention relates to devices for connecting ends of flexible bands, ropes and the like.

The invention is primarily intended for use in situations where bundles or packages of the same, or approximately the same, size are frequently being made up, tied for transportation to another department of the plant, and then released for further treatment, and where the fastening device may accompany the bundle and be reclaimed for future use, as for instance in book binderies and printing plants where signatures are tied in bundles for convenience and safety in transportation to another department of the same plant.

The object of the invention is to provide a simple and inexpensive device by means of which a cord may be quickly secured about a package or bundle and quickly removed without cutting or untying, thus saving both time and material.

The invention consists of a block having a bore, in which a cord may be secured, and a slot or slots, into which the free end of the cord may be passed and by which it may be held. The slot or slots may comprise bores having passages leading therefrom to a side of the block and the cord may be provided with a knot resting against the surface of the block at a point between the slots. An embodiment of the invention is illustrated in the accompanying drawing, in which:

Figure 1 is a perspective view of a tying device constructed according to my invention,

Figure 2 is a front view of a stack of material bound by a cord having its ends connected by one of my improved tying devices, and

Figure 3 a fragmentary bottom plan view of the stack of material and tying device shown in Figure 1.

The device consists of a block 5 having a central longitudinal bore 6 flanked on either side by parallel recessed slots 7 and 8 whose recesses or bores 9 and 10 are preferably slightly larger than a cord 11 which is passed through central bore 6 and has a knot 12 of greater diameter than the central bore or other enlargement formed in or secured to

one end. The entrances to slots 7 and 8 are preferably a snug fit for cord 11 or of slightly less width than the diameter of the cord and all corners and edges coming in contact with the cord should be chamfered so as to reduce the wear on the cord to a minimum. As shown in Figure 2, cord 11 may be wrapped around a stack 13 of material and its free end 14 secured in slots 7 and 8.

There are several methods of securing the free end of the cord in the block but the most convenient and rapid way is to grasp block 5 in the left hand and end of the cord 14 in the right hand, place the cord under sufficient tension, pass it behind the block, downwardly through slot 7, around knot 12, and upwardly through slot 8, the hand making substantially a continuous movement and the operation consuming but a fraction of the time required to tie a knot.

Another manner of using the device is to pass the free end 14 upwardly through slot 7, downwardly behind the back of block 5 and upwardly through slot 8 and is, perhaps, the best method of fastening the free end of the cord when it is desired to keep the bight of the cord under as great a tension as is possible. The first mentioned method, however, is quicker. To remove the device, the free end is simply pulled out of the slots.

The device as illustrated in the accompanying drawings and described in the preceding paragraphs is illustrative of my invention and it is to be understood may be departed from in detail within the scope of the invention as measured by the appended claims.

I claim:

1. A tying block having a central bore extending therethrough and a bore at each side of the central bore and parallel therewith, the block further having slots in one of its sides which form entrances to the side bores and which are of slightly less width than the diameter of the cord with which the device is to be used, the bores being slightly greater in diameter than the diameter of the cord.

2. A tying block having a series of bores through its greatest dimension, the outer

bores having slots parallel and co-extensive therewith and of less width than the diameter of the bores and extending from one side of said block and communicating with said bores.

5 In testimony whereof I have signed my name to this specification.

JOHN LAWLER MORGAN.
